UNITED STATES PATENT OFFICE.

JOHN DAVID STIRCKLER, OF BOSTON, MASSACHUSETTS, ASSIGNOR OF ONE-HALF TO EBENEZER FRANCIS BUMPUS, OF SAME PLACE.

FASTENER-SOCKET.

SPECIFICATION forming part of Letters Patent No. 570,069, dated October 27, 1896.

Application filed September 19, 1895. Serial No. 562,981. (No model.)

To all whom it may concern:

Be it known that I, JOHN DAVID STIRCKLER, of Boston, in the county of Suffolk and State of Massachusetts, have invented a new and useful Improvement in Fastener-Sockets, of which the following is a specification.

Referring to the accompanying drawings, Figure 1 is a plan, and Fig. 2 an edge, view of the blank from which the socket of my improved fastener is made. Fig. 3 is a top plan view, Fig. 4 a side elevation, and Fig. 5 a bottom plan view, of a socket formed by cutting the blank shown in Figs. 1 and 2, these views being enlarged for greater clearness. Fig. 6 shows the exterior spring detached. Fig. 7 shows a section of the socket and spring assembled and on a large scale. Fig. 8 is a sectional view, enlarged, showing the fastener and socket (with a button attached) and the fastener-stud, each secured to stock in co-operative position. Figs. 9 and 10 show a modification in which the spring-ring is applied to a flanged eyelet forming part of a fastener.

The object of my invention is to produce a cheap and at the same time a strong and durable fastener-socket for the reception of a detachable stud; and my invention consists, mainly, in the combination of a fastner-socket having at its mouth a slit wall and below its mouth a neck surrounded by an exterior spring-ring, and having at its outer end above the spring-ring an extension for attachment of stock above the spring-ring.

In the drawings illustrating the principle of my invention and the best mode now known to me of applying that principle, *a* is the preferred form of blank from which the fastener-socket *b* is formed, (by cupping operations readily understood by all skilled in the art without particular description,) and *b'* are the marginal slits which permit the cup to yield at its edge *b*² for the reception of the stud *d* when it is inserted, the head *d'* of the stud being a little larger than the mouth of the cup, as will be readily understood by all skilled in the art. Socket *b* is formed with a neck *b*³, and the margin *b*⁴ preferably has a plurality of slits *b'*, as shown, although a single slit will answer in some cases. The body or shank *b*⁵ of the socket is slightly en-

larged below neck *b*³ to accommodate the slightly-enlarged head *d'* of the stud *d*, and is extended above or beyond the spring-ring for connection with stock *h* above or beyond the spring-ring. The proper resiliency is given to the mouth *b*² of my new socket (whatever the details of its construction, which may be varied, if desired) by the exterior spring-ring *f*, preferably formed of a section or piece of spring-wire, as shown. The spring-ring is of an interior diameter proper to make it nicely fit and hug the neck *b*³, whereby it is kept permanently in place; and this combination of a fastener-socket, with an exterior spring-ring, is wholly new with me and results in a very simple and durable fastener-socket, the spring-rings *f* and sockets *b* being readily assembled by hand or by machines, as desired. Socket *b* is readily adapted to carry a button or to be otherwise secured to stock or fabric by means of a central hole *b*⁶, which receives a post *g* or the like, passed through the stock *h* and upset within the socket at *g'*, as will be readily understood by all skilled in the art; but my new socket may be attached to the stock in any other manner, as by sewing or by an eyelet, without departure from my invention.

Heretofore the spring members or portions of sockets relied on to receive and hold the detachable stud have become set or lost their resiliency after use. My new exterior spring-ring keeps the stud-receiving parts of the socket in proper position and is a permanently resilient backing therefor, and this exterior spring-ring is the salient feature of my improved socket.

In Figs. 9 and 10, showing a modification, my new exterior spring-ring is applied to a split eyelet and serves to hold the spring members thereof in permanently-resilient condition.

What I claim is—

1. The herein-described combination with a slit socket having a neck; a spring-ring around said neck; and an extension beyond the ring; of a flanged post secured to said extension; and stock secured between said ring and flanged post.
2. The herein-described combination of a slit socket having a neck reduced in diameter

to form a ring-seat, and having beyond the ring-seat a converged, apertured extension, with a post entered in said aperture and upset within the converged extension of the 5 socket; said post being formed with a flange at its outer end and having a body portion between said socket extension and said flange.

In testimony whereof I have signed my

name to this specification, in the presence of two subscribing witnesses, on this 14th day 10 of September, A. D. 1895.

JOHN DAVID STIRCKLER.

Witnesses:

EDWARD S. BEACH,
A. I. CRAWFORD.
